UNITED STATES PATENT OFFICE.

CHARLES NUHRING, OF CINCINNATI, OHIO.

HOSE-RACK.

No. 838,207.

Specification of Letters Patent.

Patented Dec. 11, 1906.

Application filed December 1, 1904. Serial No. 285,083.

To all whom it may concern:

Be it known that I, CHARLES NUHRING, a citizen of the United States, residing at Cincinnati, in the county of Hamilton and State of Ohio, have invented certain new and useful Improvements in Hose-Racks; and I do hereby declare the following to be a full, clear, and exact description of the invention, such as will enable others skilled in the art to 10 which it appertains to make and use the same.

This invention relates to improvements in racks for the storage of fire-hose, either of unlined linen, rubber-lined cotton and linen, or hose of other fabric.

15 The present invention contemplates the provision of a rack of the character mentioned embodying in its construction a simple arrangement of suspending-pins upon which the hose is hung in consecutive, independent, 20 and separated folds or loops of any desired length, so that the same is free to the air to permit circulation of the latter about the folds or loops, and thereby prevent decay or deterioration of the hose.

25 The invention also aims to provide in the construction of the rack simple and efficient means whereby the pins are so related to the support as to be freely movable thereon, thus enabling the hose when pressure is applied to 30 the nozzle to be quickly removed from the rack, the pins swinging to the necessary angle or in line with the direction of pressure or pull exerted upon the nozzle.

Furthermore, the invention also has in view 35 the provision of other means whereby the suspending means may be held in their normal position against movement other than when pressure is applied to the hose-nozzle and by which the rack as an entirety may be 40 movably suspended in relation to the water-supply valve to which the hose is connected.

Having these general objects in view and others, which will appear as the nature of the improvements is better understood, the invention 45 consists, substantially, in the novel construction, combination, and arrangement of parts hereinafter fully described, illustrated in the accompanying drawings, and finally pointed out in the appended claims.

50 While the forms of the invention illustrated and described are exemplifications of the preferred constructions, they are simply illustrative of the adaptation of the invention, and consequently it is to be understood

that the invention is not limited to only the 55 constructions defined herein, but the same is susceptible of other changes and modifications, and the right is therefore accordingly reserved to resort to all such changes and modifications as may fall within the spirit 60 and scope of the invention, irrespective of the forms illustrated and described.

In the drawings, Figure 1 is a front elevation of a hose-rack constructed in accordance with the present invention. Fig. 2 is a plan view thereof. Fig. 3 is a transverse sectional view taken through the support at the pivotal point of one of the suspending-pins. Fig. 4 is a rear elevation of the rack. Fig. 5 is a detail perspective view of one of the suspending-pins. Fig. 6 is a side elevation of another form of the invention, wherein the suspending-pins are arranged in different horizontal planes. Fig. 7 is a front elevation of a further form of the invention, in which is used 75 an attaching-bracket whereby the support is applied to the water-supply valve and also disclosing a duplex form of support. Fig. 8 is a plan view thereof, the dotted lines indicating the folds or loops of the hose. Fig. 9 is 80 an edge elevation of the form shown in Figs. 7 and 8. Fig. 10 is a front elevation of the attaching-bracket employed in the form disclosed in Figs. 7, 8, and 9. Figs. 11 and 12 are also elevations illustrating the flexibility 85 of application of the form illustrated in Figs. 7, 8, and 9.

Referring to the drawings in detail, and more especially to Figs. 1 to 5, inclusive, the numeral 1 designates the support of the herein-described rack, which support is preferably in the form of angle-iron including horizontal and vertical flanges. This support is secured to a wall or other base in any suitable manner, the vertical flange of the support 90 resting thereagainst and being held thereon by any suitable fastening means, preferably bolts, although it is obvious that brackets may be employed if such be necessary.

The horizontal flange of the support 1 is 100 provided with a series of longitudinally-alined openings 2, wherein is seated a series of freely-movable suspending-pins 3, from which the hose may hang in consecutive, independent, and separated folds or loops, as 105 clearly shown in the drawings. Each of the pins 3 has an elbow 4 formed at one of its ends, which elbows pass through the openings

2 and engage the under side of the support 1 in order to prevent displacement of the pins from said support. It will also be observed that the elbows form the pivotal points upon 5 which the pins 3 swing, and said pins are freely movable in the direction of the length of the support, as will presently appear.

The normal position of the pins 3 is at right angles to the support 1, in which position the 10 folds or loops of the hose are effectually suspended, as is readily apparent, and in order to maintain the pins 3 in this normal position the support 1 is provided with a series of transversely-extending depressions 5, one of 15 which lies opposite to each of the openings 2, said depressions being formed in the upper face of the horizontal flange of the support and receiving the under edges of the pins. In this position it is obvious that said pins will 20 be prevented swinging in either direction until pressure is applied upon the hose-nozzle, whereupon all of the pins will be drawn in the direction of the pressure or pull exerted upon the nozzle, thus freeing the respective folds 25 or loops of the hose and permitting the latter to be readily removed from the rack in an expeditious manner.

By referring especially to Fig. 4 it will be observed that the under side of the horizontal flange of the support is provided with a series of transversely-extending ribs 6, with which ribs the elbows 4 of the pins 3 coact. The upper faces of the elbows 4 are beveled or rounded, as at 7, in order that a 30 free sliding movement may be had in the passage of the elbows over said ribs, and by reason of this construction it will be seen that when the pins are seated in the depressions 5 the upper surfaces of the elbows are immediately beneath said ribs, but that as soon as 35 pressure is applied to the pins in the removal of the hose the curved or beveled faces of the elbows permit the elbows gradually moving toward the under side of the support as the pins ride up the ends of the depressions 5. The ribs 6 therefore guide the elbows during 40 the swinging movements of the pins 3, and consequently the latter move with a high degree of freedom and ease relatively to the support. 45

In Fig. 6 is illustrated a further form of the invention, and by referring to this figure it will be observed that this form is essentially the same as that disclosed in Figs. 1 to 5 so 50 far as the relation of the pins 3 to the support is concerned; but in this form a different type of support is employed, the same comprising a frame 8, pivotally connected, as at 9, to a stand-pipe 10 or to a wall should a 55 stand-pipe not be employed as the supporting medium. The frame 8 is provided with a series of steps 11, each of which is provided with one of the suspending-pins, and consequently it will be seen that each of these pins 60 is arranged in a different horizontal plane

from the others, whereby different lengths of folds or loops may be had in hanging the hose upon the rack. This provides for a greater exposure of the hose in a more condensed space, thus enabling the air to freely circulate 70 about the entire length of the hose to prevent its deterioration.

Figs. 7 to 10, inclusive, illustrate a further form of the invention, and in this form the support is designed to be connected directly 75 to the water-supply valve, so that the rack will be in close proximity thereto. To the accomplishment of this end an attaching-bracket 12 is employed, said bracket being in the form of an elongated bar, one end of 80 which is provided with divergent arms 12', extending from the edges of the bar and adapted to span the horizontal nipple connecting the water-supply valve 13 to a stand-pipe 14. In order that the attaching-bracket 85 12 may be freely held upon the nipple, a clamping-head 15 is employed, which clamping-head also spans the nipple of the valve 13 and is secured to the arms 12' of the bracket 12 through the medium of bolts 16 90 or their equivalent. It will thus be seen that through the medium of said bolts and the clamping-head 15 the bracket 12 may be firmly held in relation to the water-supply valve 13 and by means of said bracket the 95 hose-support may be readily attached to and held upon the nipple of a stand-pipe when the latter is concealed within or in rear of a wall, thus precluding the use of boards or wall-plates for fastening the support to the wall 100 and preventing the latter being marred.

The end of the bracket 12 opposite to that which is connected to the nipple of the supply-valve 13 is provided with a pair of parallel-spaced lugs 17, and pivotally arranged between said lugs by means of a bolt 18 or its equivalent is the horizontal support 19, from which the hose is suspended.

In the form of the invention illustrated in Figs. 7 to 10, inclusive, this support is a duplex one, comprising a head 20 and a pair of parallel arms 21, extending therefrom. The arms 21 are each provided with a series of inwardly-extending suspending-pins 22, and the construction of these pins and their relation to the support 19 are precisely the same as in Figs. 1 to 6. It will be observed, however, that the outermost of the pins 22, or those which are arranged at the free ends of the arms 21, may be swung entirely around said 110 ends, as clearly illustrated by the dotted lines in Fig. 8. The purpose of this is to permit the free removal of the outermost fold or loop of the hose and to prevent any impediment or obstacle being in the path of the other 115 folds or loops as the latter are released.

In Figs. 11 and 12 is shown the flexibility of application of the form illustrated in Figs. 7 to 10, and in these figures it will be noted that the rack may be either arranged below 120

the supply-valve 13, as in Fig. 11, or to one side thereof, as in Fig. 12, and these figures will also suggest the adaptability of the rack at any other angle to said valve. In Fig. 11, however, a brace 23 may be applied to the free end of the attaching-bracket 12 in order that the weight of the hose upon the support will be prevented forcing the latter out of a vertical plane, the brace 23 being designed to rest against the stand-pipe 14, as clearly seen.

In the forms of the invention shown in Figs. 1 to 12, inclusive, it is clearly apparent that when occasion requires the use of the hose it is merely necessary to grasp the nozzle thereof and then by exerting pressure thereon the respective folds or loops in the hose as suspended from the rack will be consecutively removed, the pins swinging in the direction of the pressure or pull upon the hose-nozzle and enabling the hose to be expeditiously taken from the rack and led to the point of use. It is also obvious that in lieu of the duplex form of the support, as shown in Figs. 7 to 12, said support may comprise only a single arm, as disclosed in Fig. 1, which is an obvious change. The bracket 12 also provides an effective medium for applying the hose-support in close proximity to the side of a wall, so that the latter will not be marred or disfigured, as would be the case were not such bracket used.

Having thus described the invention, what is claimed as new, and desired to be secured by Letters Patent of the United States, is—

1. A hose-rack, comprising a support, and a series of hose-suspending pins pivotally connected thereto, said support having a series of depressions for receiving said pins to hold the latter in their normal position upon said support until pressure is applied to the hose for removal of the latter from the rack.

2. A hose-rack, comprising a support, and a series of hose-suspending pins pivotally connected thereto, said support having a series of depressions extending transversely thereof for receiving said pins to hold the latter in their normal position upon said support until pressure is applied to the hose for removal of the latter from the rack.

3. A hose-rack, comprising a support, and a series of hose-suspending pins pivotally connected thereto and movable thereon in the direction of the length of said support, said support having a series of depressions for receiving said pins to hold the latter in their normal position upon said support until pressure is applied to the hose for removal of the latter from the rack.

4. A hose-rack, comprising a support, and a series of hose-suspending pins pivotally connected thereto and movable thereon in the direction of the length of said support, said support having a series of depressions for receiving said pins to hold the latter in their normal position upon said support until pres-

sure is applied to the hose for removal of the latter from the rack, said depressions extending transversely of said support, whereby said pins, when in their normal position, extend at right angles to said support.

5. A hose-rack, comprising a support having a series of openings formed therein, and a series of hose - suspending pins pivotally mounted in said openings, each of said pins having an elbow formed upon one of its ends, 75 said elbows being seated in said openings and engaging the under face of the support to prevent displacement of the pins from the latter.

6. A hose-rack, comprising a support having a series of openings formed therein, a 80 series of hose - suspending pins pivotally mounted in said openings, each of said pins having an elbow formed upon one of its ends, 85 said elbows being seated in said openings and engaging the under face of the support to prevent displacement of the pins from the latter, and means for holding said pins in their normal position upon said support until pressure is applied to the hose for removal of the latter from the rack.

7. A hose-rack, comprising a support having a series of openings formed therein, a series of hose - suspending pins pivotally mounted in said openings, each of said pins having an elbow formed upon one of its ends, 95 said elbows being seated in said openings, and a series of ribs formed at the under side of said support and with which said elbows coact for guiding the pins in their movement upon said support.

8. A hose-rack, comprising a support having a series of openings formed therein, a series of hose - suspending pins pivotally mounted in said openings, each of said pins having an elbow formed upon one of its ends, 105 said elbows being seated in said openings, a series of ribs formed at the under side of said support and with which said elbows coact for guiding the pins in their movement upon said support, and means for holding said pins in 110 their normal position upon said support until pressure is applied to the hose for removal of the latter from the rack.

9. A hose-rack, comprising a support having a series of openings formed therein, a 115 series of hose - suspending pins pivotally mounted in said openings, each of said pins having an elbow formed upon one of its ends, 120 said elbows being seated in said openings, and a series of ribs formed at the under side of 125 said support and with which said elbows coact for guiding the pins in their movement upon said support, the upper faces of said elbows being beveled or curved to facilitate movement of the latter in relation to said ribs.

10. A hose-rack, comprising a support having a series of openings formed therein, a series of hose - suspending pins pivotally mounted in said openings, each of said pins having an elbow formed upon one of its ends, 130

said elbows being seated in said openings, a series of ribs formed at the under side of said support and with which said elbows coact for guiding the pins in their movement upon said support, the upper faces of said elbows being beveled or curved to facilitate movement of the latter in relation to said ribs, and means for holding said pins in their normal position upon said support until pressure is applied to

the hose for removal of the latter from the rack.

In testimony whereof I affix my signature in the presence of two witnesses.

CHARLES NUHRING.
